YARN GUIDE

John J. McDonough, Laconia, N. H., assignor to Scott & Williams, Incorporated, Laconia, N. H., a corporation of Massachusetts

Application May 31, 1955, Serial No. 512,159

4 Claims. (Cl. 66—125)

This invention relates to yarn guides for knitting machines and has particular reference to yarn guides which will successfully withstand the abrasive action of synthetic yarns such as nylon.

The handling of nylon yarn in knitting machines presents a considerable problem in that in view of its abrasive quality it will rapidly cut a groove in a guide opening formed in a steel guide member. To avoid this, various types of bushings or eyes have been inserted in guide members for the passage of nylon yarn and those which appear to be most satisfactory have been made of ceramic material. But such ceramic eyes have usually involved relatively large space requirements which are inconsistent with limited spaces which are available, for example, in connection with the feeding of yarns in knitting machines wherein there are provided a number of closely associated yarn fingers selectively movable into feeding position and desirably so constructed as to effect the feeding of the various yarns from substantially the same location relative to a particular phase of movement of needles. Heretofore, in feeding relatively non-abrasive yarns such fingers have been comprised in a stack of relatively thin metal members provided with openings so that, as they move into adjacent positions, the several yarns passing through the openings would be fed from approximately the same location at the edge of a throat plate. If ceramic eyes are provided in such fingers, the required dimensions were generally such as to cause the several yarns to be fed from rather different locations with consequent disturbing of relationship of the line of feed to the needles.

Another difficulty arising in the use of ceramic eyes lies in their mounting in a carrier member.

In accordance with the present invention, yarn guides for abrasive yarns are provided which, though of metal which would normally be readily grooved by the yarn, are so arranged with freedom to revolve that they are merely polished rather than cut by the yarn and as a consequence have long life.

The general object of the invention is to provide yarn guides of the type indicated for knitting machines, and this object together with others relating to details of construction and operation will become apparent from the following description, read in conjunction with the accompanying drawing, in which:

Figure 1 is a fragmentary view, partly in section, showing the improved type of yarn guide used in a knitting machine; and

Figure 2 is a view similar to Figure 1 but showing a different path of passage of the yarn through the guide.

While the invention will be described as applied to a main yarn feeding finger of a knitting machine, it will be evident that the invention is also applicable to provide guides associated with wrap yarn carriers.

There is indicated at 2 the throat plate of a conventional circular knitting machine with which are associated a number of yarn fingers 4 of which one is shown but

2

which would, as usual, be located side by side and pivoted either to raised position above the throat plate, wherein their yarns would be withdrawn from action, or, as illustrated, resting on the throat plate in position so that their yarns would pass over the edge of the throat plate to be seized by needles 6. In accordance with prior practice, these fingers 4 would be provided with ends extending toward the edge of the throat plate, the ends being provided with yarn feeding openings.

10 In accordance with the present invention, each of the yarn feeding fingers 4, without the end just mentioned, has soldered thereto at 10 a wire 8 desirably of spring material and flexible, which wire is deflected forwardly, then downwardly, and finally backwardly as indicated at 12 to provide a mounting for tube 14, which desirably is of hardened steel, though soft steel may be used, provided with a bore considerably larger than the diameter of the wire 8 and sufficiently large to accommodate additionally the yarn 16 which is to be fed by the fingers. Initially, the ends of the bore through the tube are desirably smoothly flared outwardly and polished to provide free passage of the yarn. To give an indication of the small dimensions which may be involved in a typical arrangement the tube 14 has been approximately 15 0.16 inch in length with an outside diameter of 0.065 inch and an inside diameter of 0.035 inch, the supporting wire 8 being of 0.012 inch music wire. As indicated in the drawing, the bends of this wire above and below the tube are spaced to an extent greater than the tube 20 length so that the tube has a loose fit on the wire, being capable of freely revolving thereon.

The yarn 16 in passing through the tube may approach the tube approximately vertically but on leaving the tube will pass laterally in the direction of movement of the needles relative to the throat plate over the edge of the throat plate and thence downwardly and laterally to the position of engagement by the needles. As will be evident, such a path involves movement having a tangential component relative to the tube 14 as a result of 25 which friction will cause the tube to revolve as the yarn passes therethrough to the needles. Such revolving of the tube continuously presents new surfaces to the yarn and the result has been found in practice to be that of very slight wear on the tube or, at any rate, wear distributed so uniformly in the vicinity of the ends 30 of the tube that the guide has a very long life in contrast with an arrangement in which a similar yarn passed in a constant path relative to a fixed metallic bore. In the latter case, a groove is worn very rapidly into the 35 guide with increase of friction and possible ultimate gripping and breaking of the yarn particularly where the yarn has been knotted. In accordance with the arrangement described, the result is essentially that of mere polishing and with free movement of yarn knots through 40 the tube.

55 Figure 2 shows the yarn 16' extending through the guide of the type shown in Figure 1 in particular which involves the wrapping of the yarn 16' about the wire 8. It is found that threading of the guide in this fashion serves to promote rotation more positively than passage 60 in accordance with what is shown in Figure 1. The yarn may be wrapped in either direction about the wire 8 to provide a corresponding direction of rotation to the tube. As shown in Figure 2, the direction of rotation will be as indicated by the arrow A.

65 It will be evident from the foregoing that the invention is of quite general applicability, noting that wherever possible the tube should be so arranged that the yarn in passing through it has a tangential component of motion relative to the tube serving to rotate it frictionally to secure distribution of the location of wear. However, even without drive by the movement of the yarn vibra-

tion of the loosely mounted tube will cause it to turn at least irregularly to present new surface portions for wear.

What is claimed is:

1. Yarn guiding means comprising a tube, and a wire extending through said tube for loosely supporting the same, said tube having a bore substantially larger than said wire for the passage of a yarn therethrough and said wire having bends therein beyond the ends of the tube to confine the tube against extensive axial movement thereof.

2. Yarn guiding means comprising a metallic tube and a wire extending through said tube for loosely supporting the same, said tube having a bore substantially larger than said wire for the passage of a yarn therethrough, and said wire having bends therein beyond the ends of the tube to confine the tube against extensive axial movement thereof.

3. In a knitting machine, needles, and yarn guiding means for presenting yarn to said needles, said yarn guiding means comprising a tube and a wire-like member extending through said tube for loosely supporting

the same adjacent to said needles, said tube having a bore substantially larger than said wire-like member for the passage of a yarn therethrough.

4. In a knitting machine, needles, and yarn guiding means for presenting yarn to said needles, said yarn guiding means comprising a metallic tube and a wire-like member extending through said tube for loosely supporting the same adjacent to said needles, said tube having a bore substantially larger than said wire-like member for the passage of a yarn therethrough.
